UNITED STATES PATENT OFFICE.

EMIL PFIFFNER, OF BUDAPEST, HUNGARY.

ARRANGEMENT FOR CARRYING OFF HEAT.

Application filed May 5, 1924, Serial No. 711,249, and in Germany April 3, 1923.

It is already known to insulate the high-tension coils of transformers and the like by means of infusion in an insulating material in place of the generally used oil insulation.

In the solid condition the known insulating infusion materials possess a considerably better insulating power or property than the transformer-oils and therefore render possible smaller insulation distances and smaller dimensions of the coil or of the transformer.

However compared with the above, the infusion materials are disadvantageous, as a smaller conduction of heat is obtained and the danger of a local excessive heating is present, which may cause a destruction of the insulation of the coils.

The construction according to the present invention has for its object to remove this draw back and put on an equal footing the insulation by infusion material, with the insulation by oil.

The essential feature of the arrangement according to the present invention consists in employing the infusion material solely for the electric insulation, but to arrange good conducting heat-channels or ways for the carrying off of heat. Good heat conducting members generally also are conductors of electricity. In order that the electric insulation may not be affected due to the provision of these heat-channels, the latter should be arranged as far as possible in the equipotential surfaces of the electric field.

The arrangement is the most simple in case the transformer or the coil is disposed within an insulating casing, as in this case the equipotential surfaces transect the shell of the casing and the heat-channels or ways may pass up to the shell of the casing.

One mode of carrying out the present invention is illustrated by way of example on the accompanying sheet of drawings in which:

Fig. 1 shows a coil provided with the arrangement according to the present invention in sectional elevation, and

Fig. 2 is a cross-sectional view of the construction illustrated in Fig. 1.

Fig. 3 is a detail view in sectional elevation and on an enlarged scale.

In Figures 1 and 2, a system of high-tension coils, comprising an iron core *k* and a number of coils *s₁*, *s₂*, *s₃*, *s₄*, *s₅* which are connected in series, is encased in an insulating casing *i*.

The equipotential surfaces of the electric field are disposed essentially vertical with respect to the axis of the coils. Plates *l* of a good heat-conducting material, for instance copper, are disposed between the individual coils *s₁*, *s₂* and so forth, in order to carry off the heat generated in the coil to the shell of the insulating casing. The heat-conductivity of copper is for instance 1000 to 2000 times larger than that of the infusion material *m*, which may consist for example, of asphalt, paraffin and the like. Thus if the thickness of the plates *l* is about one twentieth of the distance between two plates, which place is filled with the material *m*, the arrangement will improve the conduction of heat 50 to 100 times, e. g. the conduction of heat is nearly exclusively carried out by the plates *l*, while the infusion material solely serves for the insulation between the surfaces of a like potential in the field-direction.

The equipotential surface of the iron-core *k* may be increased by providing wings or extensions *h* on the clamps for the core to carry off the heat generated in the iron-core and for improving the carrying off of heat and the passage of the heat to the shell of the casing.

The invention is not limited to apparatus with an insulating casing, but in the latter case the heat channels or ways may be arranged without any difficulty. In order to provide these channels or ways it is however necessary, that the equipotential surfaces of the electric field pass into a ventilated outside space.

As illustrated in Fig. 3 the heat-conducting plates may be provided with an enlarged rim or border *r*, in order to reduce the contact fall at the shell of the casing.

I claim:—

1. An arrangement for carrying off heat in an electric device, comprising in combination a casing containing a cast insulating material which has electric and thermal insulating properties, a system of coils ar-

ranged in the casing and embedded in said material, and plates having high heat-conducting properties disposed in said material in such manner, that the plates are arranged as far as possible in the equipotential surfaces of the electric field.

2. An arrangement as claimed in claim 1

in which the casing is formed of insulating material and the plates extend into close proximity to the inner surface of said casing. 10

In testimony whereof I hereunto affix my signature.

EMIL PFIFFNER.
